UNITED STATES PATENT OFFICE.

JOSEPH H. CHAMP, OF CLEVELAND, OHIO.

BOTTLING-MACHINE.

939,214.

Specification of Letters Patent. Patented Nov. 9, 1909.

Application filed May 29, 1903. Serial No. 159,246.

To all whom it may concern:

Be it known that I, JOSEPH H. CHAMP, a citizen of the United States, resident of Cleveland, county of Cuyahoga, and State of Ohio, have invented a new and useful Improvement in Bottling-Machines, of which the following is a specification, the principle of the invention being herein explained and the best mode in which I have contemplated applying that principle, so as to distinguish it from other inventions.

My invention relates to bottling machines; and consists of the means hereinafter described, and particularly pointed out in the claims.

The annexed drawings and the following description set forth in detail certain means embodying the invention, such disclosed means constituting but one of various forms in which the principle of the invention may be used.

Figure I is a perspective view. Fig. II is a detail view in transverse vertical section, the dotted lines showing certain members in the third valve operative position, and the full lines showing the said members in the second valve operative position. Fig. III is a detail view of the regulating chamber, showing certain portions broken away and certain members in side elevation. Fig. IV is a detail, partly section and partly side elevation, showing one pair of bottle mouth pieces with their coöperating means. Fig. V is mainly a section on line 1—1 of Fig. IV. Fig. VI is mainly a section on line 2—2 of Fig. IV. Fig. VII is mainly a section on line x—x of Fig. IV. Fig. VIII is mainly a section on line 3—3 of Fig. IV. Fig. IX is a detail view in transverse vertical section, and showing certain members in the first valve operative position. Fig. X is a detail view in central longitudinal section of the bottle mouth piece.

The form of the machine shown in the drawings is adapted to fill several pairs of bottles simultaneously; but it will be understood that a machine could equally well embody the invention, though such machine be adapted to at one time fill more or less number of bottles. Detail description will therefore be given of the construction and operation of the invention as embodied in means for filling a single bottle, such construction and operation being substantially the same as in means for filling at one time more than one bottle.

The beer with which the bottle is to be filled is supplied under proper pressure through horizontal conduit A, which has communication at its one end with one or more beer kegs A'. Horizontal gas supply conduit A², located higher than and parallel with beer supply conduit A, has end connection with horizontal pipe A³ which latter has end connection with one or more carbonic acid gas drums A⁴. A regulator a and a gage a' being intermediate of said A³ and A⁴. Branch pipes A⁵ connect said pipe A³ respectively with said beer kegs A', and are respectively provided with cocks a². A gas cock a⁶ is located at one end of connection A⁶ between conduit A² and pipe A³. Beer cocks a⁷ are located at opposite ends of connection A⁷ between the respective beer kegs and conduit A.

The horizontal stationary plug B, parallel with beer supply conduit A, is provided with a central longitudinal bottling fluid way b, which is in constant open communication with the lower portion of said beer supply conduit, by intermediate branch pipe a⁵.

The end of conduit A², opposite to its end connection with pipe A³, has connection A⁸ with the upper end of chamber C, and is provided with cock a⁹. Such chamber C is located rearwardly of the central length portions of conduits A and A². Its lower portion has constant connection c with the lower portion of beer supply conduit A. Its upper portion has constant connection c' with the upper portion of said beer supply conduit A, and is provided with a gage c².

Mounted on plug B so as to have an oscillatory or rocking movement with reference thereto, are suitable bottle holding means including a bottle mouth piece D and a bottle rest F adapted to receive the bottom of the bottle and to hold its mouth against such mouth-piece. Bottle mouth-piece D comprises as its base member a tubular valve portion seated around plug B. Such valve portion of mouth-piece D is provided with three fluid-ways, each divided into two transverse parts; each one of such three fluid-ways having the plug B located between its said two transverse parts. Said three two-part ways are respectively: the gas inlet way d', the vent way d², and the final relief way d³. The gas inlet way d' has its two transverse parts adapted to communicate with each other by intermediate registration of channel b', formed in plug B. The vent

way d^2 has its two parts adapted to communicate with each other by intermediate registration of channel b^2 , formed in plug B. The bottling fluid way b is provided with 5 port b^x , adapted to register under proper conditions with way d^x , formed in member D, for the beer to be bottled. The final relief way d^3 has its two parts adapted to communicate with each other by intermediate 10 registration of channel b^3 , formed in plug B. A tube E has its upper end detachably threaded in the lower portion of bottling fluid way d^x , and has its lower end adapted to discharge into the bottom of the bottle the beer 15 from conduit A. The formation of the said ways is such that the two transverse parts of gas inlet way d' register with channel b' , and complete operation resulting from such registration, and pass out of such registration, 20 all before the two transverse parts of vent way d^2 register with channel b^2 , and also all before port d^x registers with port b^x . The bottle is thereby fully charged with the 25 gas before beer communication with the bottle is had, and before vent is given to the bottle; whereby there is insured within the bottle a pressure equal to that of the beer, before communication is opened between the bottle and the beer. After said three ways 30 have had their coöperating parts register with each other, and have passed out of such registration,—then, the coöperating parts of the final relief way register and relieve any pressure of air or gas within the bottle, so 35 that the latter may be removed from the machine without overflow of any of the beer.

Bottle filling tube E is connected to and depends from port b^x , down through tubular formation e^e' depending from annular plate 40 e^3 fitted between the upper face of gasket d and supporting member D; such gasket having thereby formed in its central upper portion chamber e^2 from which a passage of less diameter than said chamber depends, 45 through which chamber and passage said tube E depends clear thereof. Nut d^4 is threaded to the lower portion of depending annular wall d^5 of said supporting member D, within which wall said gasket is fitted, 50 and clamps together said gasket and plate and supporting member.

The bottle-rest F is cup-shaped on its upper surface, adapted to receive and closely hold the bottom of a bottle of corresponding size. A rod G has its upper extremity rigidly connected to arm L, and has its depending portion passing freely through an opening in the rear portion of rest F, so as to have loose engagement with such 55 rest. A spiral spring H is loosely fitted about said rod, being compressed between the rest F and a clip h on said rod, which clip may be maintained at different points of vertical adjustment on said rod by thumb-

screw h'. A rod J projects rearwardly from rest F angularly to said rod G and is adapted to have longitudinal travel beneath roller j, fastened by clamp K to the framework of the machine, such clamp having its lower portion slotted and adapted to be maintained at different points of vertical adjustment on the machine-framework by clamping-bolt k, fitted within the slotted portion. 65

Member D is provided with rigid rearwardly-projecting arm L, to whose outer end is pivoted the shank of a hook l, such hook passing over a rod M of the machine-framework. A coil spring N has its one end connected with said rod M, and its other end connected with said arm L; the construction being such that said spring exerts pressure upon said arm L, with tendency to throw the latter into desired position, respectively after the pivotal connection of said arm and hook has passed dead center. 75

The pressure regulating chamber C is provided with a valve O, whose stem o loosely works in vertical channel o', formed in the center of the cap of chamber C. Said vertical channel o' communicates at its upper 80 end with channel o², which latter is provided with vent cock o³. The lower end of vertical channel o' communicates with the interior of the chamber C. Valve O opens and closes communication between said channel o' and the upper end of said chamber O; such valve being operated by ball float O' and intermediate lever device O². 85

Tube R constantly connects the upper part of gas inlet way d' with the gas supply conduit A². Tube R' is adapted to constantly connect the upper part of vent way d^2 with the upper portion of beer supply conduit A, by intermediate branch pipe a⁷, the connection being subject to control by means of interposed cocks a⁸. 100

At the commencement of use of the machine, cock a⁶ is opened and left open until the gage on the regulating chamber shows about the same pressure as the gage on the 110 gas supply tanks A⁴. Thereupon cock a⁶ is closed, cocks a² opened and beer turned onto the machine by opening cocks a⁴. Pending this turning on of the beer, cock o³ is opened slightly so as to let the air out of the machine very slowly until the float in the regulating chamber rises, thus automatically stopping such escape of air; cock o³ is then opened wide. The actual bottling operation may now be undertaken, cocks a⁸, as 115 well as cocks o³, being open during such operation.

Carbonic acid gas, under suitable pressure as regulated by the cocks, passes into the upper portions of the beer kegs, and also into 120 gas supply conduit A². Suitable manipulation of the various cocks results in the automatic operation of the machine; filling the 125

bottle with gas under pressure such as to cause the beer under like gas pressure to flow into the bottle solely by gravity, as such beer displaces the gas with which the bottle was 5 previously charged. The air or gas or foam, displaced from the bottle, passes up into the upper portion of beer supply conduit A, and from thence into the upper portion of regulator C. The float controlled 10 valve escape in the latter maintains conditions of desired pressure and also of the liquid level within such regulator. After the gas inlet way and the beer inlet way and the vent way have all performed their respective duties, and are closed against operation,—then the final relief way opens and operates to relieve the pressure that is in the bottle, preparatory to clean removal of the latter from the machine.

20 Assuming that a bottle is to be filled with beer, the bottle is placed in the machine between the mouth-piece and the rest, the members of the machine thereby being in position whereby the bottle is properly locked 25 in place in the machine. The bottle is then pushed slightly rearward, so as to place the members of the machine in the first operative position, (shown in Figs. V and IX), wherein the gas-inlet way d' is open, so as 30 to permit gas under pressure from the gas supply conduit to pass into the bottle. The latter is then moved still farther rearwardly, thereby placing the members of the machine in the second operative position, (shown in 35 Figs. IV, VI, VII, and in full lines of Fig. II) wherein vent way d^2 permits air or gas or foam, to pass out from the bottle sufficiently to permit the beer under like pressure within conduit A to pass, solely by gravity, 40 into the bottom of the bottle. The bottle being then filled, it is moved forwardly, so as to place the members of the machine in the third and final operative position, (shown in dotted lines of Fig. II, and in 45 Fig. VIII,) wherein the final relief way d^3 is open, so as to permit escape from the bottle of any air or gas that might otherwise cause any of the beer to fly out of the bottle when the latter is removed from the mouth-piece. The bottle may then be taken from 50 the machine and corked.

The invention may be used to bottle any suitable fluid. Wherever the term beer occurs in the foregoing description or the following claims, the same should be understood as including, under the rule of equivalents, any suitable fluid, as a known substitute for beer.

The invention may be used with any suitable fluid passing through the conduit set forth in the foregoing description as being for the passage of carbonic acid gas.

Wherever the term gas or carbonic acid gas occurs in the foregoing description or the following claims, the same should be

understood as including, under the rule of equivalents, any suitable fluid, as a known substitute for carbonic acid gas.

Other modes of applying the principle of my invention may be employed instead of the one explained, change being made as regards the mechanism herein disclosed provided the means stated by any one of the following claims or the equivalent of such 75 means be employed.

I therefore particularly point out and distinctly claim as my invention—

1. In a bottle filling machine, the combination of a liquid supply, a chamber provided with fluid pressure regulating mechanism, said chamber having its upper portion communicating directly with the upper portion of said supply and having its lower portion communicating directly with the lower portion of said supply, a fluid pressure 80 supply apart from said liquid supply and said chamber, and a bottle mouth-piece adapted to have connection with liquid and fluid-pressure supplies, respectively.

2. In a bottle filling machine, the combination of a liquid supply, a chamber provided with fluid pressure regulating mechanism, fluid communication directly between the upper portion of said supply and the upper portion of said chamber, fluid communication directly between the lower portion of said supply and the lower portion of said chamber, a fluid-pressure supply 95 apart from said liquid supply and said chamber and a bottle mouth-piece having 100 several fluid ways, one of said ways adapted to provide communication between the upper portion of said liquid supply and said mouth-piece, another of said ways adapted to provide communication between the lower portion of said liquid supply and said mouth-piece, and yet another way adapted to provide communication between said fluid-pressure supply and said mouth-piece.

3. In a bottle filling machine, the combination of a liquid supply receptacle, a bottle mouth-piece, a way having valve means and connecting said mouth-piece directly with the upper portion of said supply receptacle, a way having valve means and connecting said mouth-piece directly with the lower portion of said supply receptacle, each such way connected directly to said mouth-piece separately from the connection of the other way, a chamber provided with 110 fluid pressure regulating mechanism, a way connecting the upper portion of said chamber and the upper portion of said supply receptacle, and a way connecting the lower portion of said chamber and the lower portion of said supply receptacle.

4. In a bottle filling machine, the combination of a liquid supply source, a bottle mouth-piece, ways between said two members, respectively adapted to connect the 125

lower and upper portions of said supply source directly with said mouth-piece, valve means controlling said ways, a chamber distinct from said supply source and provided, 5 with fluid pressure regulating mechanism, a way providing constant communication between the upper portion of said chamber and the upper portion of said supply source, and a way providing constant communication 10 between the lower portion of said pressure regulating chamber and the lower portion of said supply source.

5. In a bottle filling machine the combination of a liquid supply receptacle and 15 pressure-fluid supply receptacle relatively distinct, pressure regulating mechanism for said liquid supply, a bottle mouth-piece, a way connecting said mouth-piece with said fluid-pressure supply receptacle, a way connecting 20 said mouth-piece directly with the upper portion of the liquid supply receptacle, a way connecting said mouth-piece directly with the lower portion of the last named supply receptacle, each such way being connected directly to said mouth-piece 25 separately from the connection of any other way, and unitary valve means controlling said ways, substantially as set forth.

6. In a bottle filling machine, the combination of a liquid supply receptacle and a 30 pressure-fluid supply receptacle relatively distinct, a bottle mouth-piece, a way having valve means and connecting said mouth-piece with said fluid pressure supply receptacle, a way having valve means and connecting said mouth-piece directly with the upper portion of the liquid supply receptacle, a way having valve means and connecting said mouth-piece directly with the 35 lower portion of said last named supply receptacle, each such way being connected directly to said mouth-piece separately from the connection of any other way, a chamber provided with fluid pressure regulating mechanism, a fluid way connecting the upper portion of said chamber and the upper portion of said liquid supply receptacle and a fluid way connecting the lower portion of said chamber and the lower portion of 40 said liquid supply receptacle.

7. In a bottle filling machine, the combination of a liquid supply receptacle and a fluid-pressure supply receptacle relatively distinct, a bottle mouth-piece, a chamber 45 provided with fluid-pressure regulating mechanism, a way having valve means and directly connecting said fluid-pressure supply receptacle with said mouth-piece, a way having valve means and connecting said 50 mouth-piece directly with the upper portion of the liquid supply receptacle, a fluid way having valve means and connecting said mouth-piece directly with the lower portion of the last named supply receptacle, each 55 such way being connected directly to said

mouth-piece separately from the connection of any other way, a way connecting the upper portion of said chamber and the upper portion of said liquid supply receptacle, a way connecting the lower portion of said liquid supply receptacle and the lower portion of said chamber, and a way having valve means and directly connecting said fluid pressure supply receptacle with said chamber. 70

8. In a bottle filling machine, the combination of two conduits, a chamber provided with fluid-pressure regulating mechanism, said three members being separate from each other but said chamber having connection 80 with one of said conduits, a bottle mouth-piece having at least three distinct ways, one of said ways adapted to connect said mouth-piece with one of said conduits, another of said ways adapted to connect said mouth-piece directly with the upper portion of the remaining conduit, and another of said ways adapted to connect said mouth-piece directly with the lower portion of said remaining conduit. 85

9. In a bottle filling machine, the combination of two conduits, a chamber provided with fluid pressure regulating mechanism, said three members being separate from each other, but said chamber having distinct ways 90 adapted to directly communicate respectively with the upper portion and with the lower portion of one of said conduits, and a bottle mouth-piece having distinct ways adapted to connect it respectively with said 95 two conduits.

10. In a bottle filling machine, the combination of a gas supply conduit, a beer supply conduit, a chamber provided with fluid pressure regulating mechanism, said three 105 members being separate from each other, but said chamber having distinct ways adapted to directly communicate respectively with the upper portion and with the lower portion of said beer supply conduit, 110 and a bottle mouth-piece having distinct ways adapted to connect it respectively with said two conduits, said gas supply conduit being adapted to have communication directly with said pressure regulating chamber. 115

11. In a bottle filling machine, the combination of two distinct fluid supply sources, a bottle mouth-piece, three distinct fluid ways respectively adapted to connect one of said 120 supply sources with said mouth piece and the lower and upper portions of the remaining supply source directly with said mouth piece, and unitary valve means controlling said ways, to effect such connections in the 125 order named when filling a bottle.

12. In a bottle filling machine, the combination of a gas supply conduit, a beer supply conduit, a chamber provided with pressure regulating mechanism, the upper portion of 130

said chamber communicating directly with the upper portion of said beer supply conduit and the lower portion directly with the lower portion of said beer supply conduit, 5 and a bottle mouth-piece having distinct ways adapted to connect it respectively with said two conduits, said gas supply conduit being adapted to have communication directly with said regulating chamber.

10 13. In a bottle filling machine, the combination of two distinct conduits, a chamber provided with pressure regulating mechanism, the upper portion of said chamber communicating directly with the upper portion 15 of one of said conduits and the lower portion directly with the lower portion of the same conduit, and a bottle mouth-piece having several distinct ways, one of said ways being adapted to connect said mouth-piece directly with the lower portion of said last identified conduit, and another of said ways being adapted to connect said mouth piece with the remaining conduit.

14. In a bottling machine, the combination of two superposed fluid supply receptacles relatively distinct, a bottle mouth piece having several distinct ways, one of said ways adapted to connect said mouth piece directly with the upper portion of the 25 lower of said receptacles, another of said ways adapted to connect said mouth piece directly with the lower portion of said last identified receptacle, another of said ways adapted to connect said mouth piece with 30 the upper receptacle, and means controlling such connections whereby the same are effected in reverse order to that named, when filling a bottle.

15. In a bottle filling machine, the combination of two distinct superposed conduits, a chamber provided with pressure regulating mechanism, the upper and lower portions of said chamber communicating directly with the upper and lower portions respectively of the lower of said conduits, a bottle mouth piece having several distinct ways, one of said ways adapted to connect said mouth piece directly with the upper portion of said lower conduit, another of 45 said ways adapted to connect said mouth piece directly with the lower portion of said last identified conduit, another of said ways adapted to connect said mouth piece with the upper conduit.

50 16. In a bottle filling machine, the combination of two distinct superposed horizontally extended conduits, a chamber provided with pressure regulating mechanism, the upper and lower portions of said chamber communicating directly with the upper and lower portions respectively of the lower of said conduits, a plurality of bottle mouth pieces alined with said lower conduit, each such mouth piece having several distinct 55 ways, one of said ways adapted to connect

said mouth piece directly with the upper portion of said lower conduit, another of said ways adapted to connect said mouth piece directly with the lower portion of said last identified conduit, another of said ways 70 adapted to connect said mouth piece with the upper conduit and means controlling such connections whereby the same are effected in reverse order to that named, when filling a bottle.

75 17. In a bottle filling machine, the combination of a gas supply conduit, a beer supply conduit, a chamber provided with pressure regulating mechanism and adapted to communicate with said gas supply conduit, 80 the upper portion of said chamber communicating directly with the upper portion of said beer supply conduit and the lower portion directly with the lower portion of said beer supply conduit, and a bottle mouth-piece having several distinct fluid ways, one of said ways being adapted to connect said mouth-piece with said gas supply conduit, one of said ways being adapted to connect said mouth piece directly with the upper 85 portion of said beer supply conduit, and one of said ways being adapted to connect said mouth piece directly with the lower portion of said beer supply conduit.

90 18. In a bottle filling machine, the combination of a gas supply conduit, a beer supply conduit, a chamber having its upper portion provided with an automatic fluid-escape device and having its upper portion and its lower portion directly communicating respectively with the upper portion and with the lower portion of said beer supply conduit, said gas supply conduit being adapted to communicate with said chamber, 95 and a bottle mouth-piece having several distinct fluid ways, one of said ways being adapted to connect said mouth-piece with said gas supply conduit, one of said ways being adapted to connect said mouth-piece directly with the upper portion of said beer 100 supply conduit, and one of said ways being adapted to connect said mouth piece directly with the lower portion of said beer supply conduit.

105 19. In a bottle filling machine, the combination of a substantially horizontal gas supply conduit, a substantially horizontal beer supply conduit, a chamber having its upper portion provided with a float controlled, fluid-escape device and having its upper portion communicating directly with the upper portion of said beer supply conduit and having its lower portion communicating directly with the lower portion of said beer supply conduit, said gas supply conduit being adapted to communicate with said chamber, 110 and a bottle mouth-piece having several distinct fluid ways, one of said ways being adapted to connect said mouth-piece with said gas supply conduit, one of said ways 115 being adapted to communicate with said chamber, and a bottle mouth-piece having several distinct fluid ways, one of said ways being adapted to connect said mouth-piece with said gas supply conduit, one of said ways 120 being adapted to communicate with said chamber, and a bottle mouth-piece having several distinct fluid ways, one of said ways being adapted to connect said mouth-piece with said gas supply conduit, one of said ways 125 being adapted to communicate with said chamber, and a bottle mouth-piece having several distinct fluid ways, one of said ways being adapted to connect said mouth-piece with said gas supply conduit, one of said ways 130 being adapted to communicate with said chamber.

being adapted to connect said mouth-piece directly with the upper portion of said beer supply conduit, and one of said ways being adapted to connect said mouth-piece directly 5 with the lower portion of said beer supply conduit.

20. In a bottle filling machine, the combination of two distinct conduits, a bottle mouth-piece having ways adapted to connect it respectively with said conduits, the way between one of said conduits and said mouth-piece being adapted to operate and close before any way between said remaining conduit and said mouth-piece is adapted 15 to open and operate, and a chamber provided with pressure regulating mechanism, said chamber having its upper portion connected directly with the upper portion of said remaining conduit and having its lower portion 20 connected directly with the lower portion of such conduit.

21. In a bottle filling machine, the combination of two distinct fluid supply conduits, a bottle mouth-piece having several distinct 25 fluid ways, one of said ways being adapted to connect said mouth-piece with one of said conduits, another of said ways being adapted to connect said mouth-piece directly with the upper portion of the remaining conduit, another of said ways being adapted to connect said mouth-piece directly with the lower portion of said remaining conduit, said way 30 between said first specified conduit and said mouth-piece being adapted to operate and close before either one of said two ways between said remaining conduit and said mouth piece is adapted to open and operate, and a chamber provided with pressure regulating mechanism, said chamber having its 35 upper portion connected directly with the upper portion of said remaining conduit and having its lower portion connected directly with the lower portion of such conduit.

22. In a bottle filling machine, the combination of two fluid supply conduits, a bottle mouth-piece having a way adapted to communicate with one of said conduits and also having two distinct ways adapted to communicate respectively with the lower portion 45 and with the upper portion of the remaining conduit, and a chamber having an automatic fluid escape device at its upper portion, said chamber being connected respectively with the upper portion and with the lower portion of said remaining conduit.

23. In a bottle filling machine, the combination of two substantially horizontal fluid supply conduits, a chamber having its upper portion provided with a float controlled 50 fluid-escape valve and having its lower portion communicating with the lower portion of one of said conduits and having its upper portion communicating with the upper portion of the same conduit, and a bottle mouth-piece having two distinct ways adapted to 55

communicate respectively with the upper portion and with the lower portion of said conduit that communicates with said chamber and also having a distinct fluid way adapted to communicate with the remaining 70 conduit.

24. In a bottle filling machine, the combination of two distinct fluid supply conduits, a bottle mouth-piece having a way adapted to communicate with one of said conduits 75 and having two distinct ways adapted to communicate respectively with the lower portion and with the upper portion of the remaining conduit, and a chamber provided with pressure regulating mechanism, said 80 chamber having distinct ways adapted to communicate respectively with the upper portion and with the lower portion of said remaining conduit, substantially as set forth.

25. In a bottle filling machine, the combination of two distinct fluid supply sources, a bottle mouth - piece, a fluid way provided with valve mechanism adapted to connect said mouth-piece with one of said two supply sources, a fluid way provided with valve 85 mechanism adapted to connect said mouth-piece directly with the upper portion of the remaining supply source, a fluid way provided with valve mechanism adapted to connect said mouth - piece directly with the 90 lower portion of said remaining supply source, a chamber provided with fluid pressure regulating mechanism and having its upper portion in constant communication with the upper portion of said remaining 95 supply source and having its lower portion in constant communication with the lower portion of said remaining supply source, such pressure regulating chamber being distinct from both said supply sources, each of 100 said three fluid ways and valve mechanisms being distinct from each of the two remaining fluid ways and valve mechanisms, substantially as set forth.

26. In a bottle filling machine, the combination of a cylinder adapted to have a continuous liquid supply at its lower part and communicating at its upper part with a chamber provided with fluid pressure regulating mechanism, means for supplying 110 compressed gas, a gas cylinder in communication at one end with said gas supply, gas connection between the other end of said gas cylinder and the top of said chamber, mouth-pieces having filling tubes adapted 115 to be connected at their upper ends with the lower part of said liquid cylinder, valved primary charging ducts leading from said gas cylinder intermediate of its ends and connecting respectively with said mouth-pieces, and valved vent ducts leading respectively from said mouth pieces to the upper portion of said liquid cylinder.

27. In a bottle filling machine, the combination of two distinct conduits, and movable 125

bottle holding means including a bottle mouth-piece, said mouth-piece having at least three distinct ways, one of said ways adapted to connect said mouth piece with 5 one of said conduits, another of said ways adapted to connect said mouth-piece directly with the upper portion of the remaining conduit, another of said ways adapted to connect said mouth-piece directly with the 10 lower portion of said remaining conduit, the connection of said ways being controlled by the movement of said bottle holding means, connection being had by said first way with said first specified conduit prior to connection by said other ways upon movement of 15 said bottle holding means.

28. In a bottle filling machine, the combination of two distinct conduits, a valve plug,

and bottle holding means including a bottle mouth piece mounted upon said plug so as to be movable thereabout, said plug and mouth piece being formed with ways adapted to successively register upon movement of the latter and connected thereupon to afford communication between said mouth-piece and 20 said first conduit, the upper portion, directly, of said second conduit and the lower portion, directly, of said second conduit, respectively, such various connection being had in the order named incidently to movement of said bottle holding means.

Signed by me, this 28th day of May, 1903:
JOSEPH H. CHAMP.
